UNITED STATES PATENT OFFICE.

EDWARD J. MAHER, OF ST. LOUIS, MISSOURI, ASSIGNOR TO P. C. MURPHY TRUNK CO.,
OF ST. LOUIS, MISSOURI, A CORPORATION OF MISSOURI.

WARDROBE-TRUNK.

1,256,344.

Specification of Letters Patent. Patented Feb. 12, 1918.

Application filed November 25, 1916. Serial No. 183,328.

To all whom it may concern:

Be it known that I, EDWARD JOSEPH MAHER, a citizen of the United States, residing at St. Louis, Missouri, have invented 5 a certain new and useful Improvement in Wardrobe-Trunks, of which the following is a full, clear, and exact description, such as will enable others skilled in the art to which it appertains to make and use the 10 same.

This invention relates to wardrobe trunks of the type in which one section of the trunk constitutes a compartment for garments that are suspended from coat hangers, and the other section of the trunk constitutes a compartment for sliding drawers, 15 boxes or containers for holding small articles.

One object of my invention is to provide 20 an efficient means of novel construction for holding the garments in the garment compartment of a wardrobe trunk in a flat condition.

Another object is to provide a follower 25 for wardrobe trunks that is held securely at its upper and lower ends and which is so constructed that it can be operated easily either to press the garments together or to release the garments when it is desired to 30 remove one of the garments from the trunk.

Figure 1 of the drawings is a perspective view of a wardrobe trunk constructed in accordance with my invention, showing the trunk open.

Fig. 2 is a front elevational view of the 35 garment section.

Fig. 3 is a vertical sectional view, taken on the line 3-3 of Fig. 2; and

Fig. 4 is an horizontal view, taken on 40 the line 4-4 of Fig. 2.

Referring to the drawings, which illustrate the preferred form of my invention, A and B designate a garment section and drawer section, respectively, of a wardrobe 45 trunk, the garment section being provided with extensible rails 1 on which coat hangers 2 are slidably mounted, and the drawer section being provided with a plurality of drawers or containers 3 that are slidably mounted on guides 4. The top portion 5 of the garment section A is hinged so that it can be raised, as shown in Fig. 1, and a metal collar or substantially U-shaped metal frame 6 is combined with said garment

section, so as to reinforce and strengthen 55 the upper end portion of same and also serve as a rigid support for the rails 1 on which the coat hangers are mounted. The parts above referred to are of well known construction and form no part of my present invention. 60

My invention consists in a means of novel construction for holding the garments in the section A of the trunk in a flat condition and in the preferred form of my invention, 65 as herein illustrated, said means consists of a follower C that is provided at its upper and lower ends with devices which coöperate with elements carried by the section A to securely hold said follower in position and 70 permit it to be adjusted toward and away from the rear wall 7 of the garment compartment of the trunk. The follower C may be of any preferred form, the follower herein shown consisting of a rectangular shaped 75 frame formed from slats, and various means may be used for supporting said follower and holding it in adjusted position. One means that I have found to be very efficient for this purpose consists of a pair of rails or 80 bars 8 arranged adjacent the upper end of the garment compartment that coöperate with laterally-projecting devices 9 on the upper end portion of the follower C to support said follower, and a spring-actuated device 10 at the lower end of the follower that coöperates with retaining devices 11 on the side walls 7a of the garment compartment. The bars or rails 8, on which the follower C 85 is slidably mounted, are preferably provided with racks or notched portions that coöperate with the laterally-projecting devices 9 on the follower to hold the follower in adjusted position, and the teeth 12 of said notched portions slope upwardly toward the 90 rear wall 7 of the garment compartment, as shown in Fig. 3, so that the devices 9 on the follower will ride freely over the rails 8 when the follower is pushed rearwardly or toward the rear wall of the garment compartment. In order to prevent the devices 9 on the follower from moving upwardly off the rails 8, I have provided said rails with retaining portion 13 that extend over the laterally-projecting devices 9 on the follower, and 95 thus prevent said devices from moving upwardly out of engagement with the teeth 12 or notched portions of the rails 8. Each of 100 105

the laterally-projecting devices 9 of the follower is provided with a reduced end portion 9^a, as shown in Fig. 2, that is positioned between the rack portion and the retaining portion 13 of the rail 8 with which said device coöperates, and while the rails 8 can be formed in various ways without departing from my invention, I prefer to form each of said rails from a flat bar of metal 10 that is bent at one end to form a right-angularly-disposed flange 14 through which fastening devices pass, and bent at its other end to form a substantially angle-shaped portion, one of whose legs serves as a spacing device to hold the bar away from the side wall of the garment compartment and the other leg serving as a flange 14^a through which fastening devices pass. The rails 8 can either be connected at their rear ends to 20 the rear wall 7 of the garment compartment and at their front ends to the side walls of said compartment, or said rails can be connected to the metal frame or collar 6 at the upper end of the garment compartment, as shown in Fig. 1. When the rails 8 are formed in the manner above referred to the slot between the toothed portion and the retaining portion 13 of each rail will extend laterally into the angle-shaped portion at 30 the front end of the rail, as shown in Fig. 1, so as to permit the reduced portions 9^a of the devices 9 to be withdrawn from said slots when it is desired to completely remove the follower C from the garment compartment.

The retaining elements 11 that coöperate with the spring-actuated device 10 at the lower end of the follower preferably consist of rack bars mounted on the side walls 7^a 40 of the garment compartment, and the device 10 on the follower that coöperates with said elements preferably consists of a transversely-disposed bar 10 whose end portions project laterally far enough from the follower to extend under the retaining elements 11 and coöperate with the teeth 11^a thereon. The bar 10 is combined with a means that tends to move said bar upwardly into engagement with the teeth 11, and in the form 45 of my invention herein shown said means consists of contractile springs 15 arranged in guiding devices 16 on the follower that receive guiding pins 17 on the bar 10, said springs being connected at their upper ends 50 to the guides 16 and at their lower ends to the guide pins 17, as shown in broken lines in Fig. 2.

When the follower is in operative position, as shown in Fig. 1, the springs 15 tend 60 to draw the follower downwardly and the bar 10 upwardly, thereby causing the devices 9 at the upper end of the follower and the device 10 at the lower end of the follower to be drawn downwardly and upwardly, respectively, into engagement with

the notched portions or rack teeth on the bars 8 and 11, respectively, with which they coöperate.

To adjust the follower C or change the position of same relatively to the rear wall 70 7 of the garment compartment, it is necessary to first depress the bar 10, so as to release the end portions of same from the retaining devices 11, then swing the follower upwardly into an inclined position or horizontal position so that the reduced portions 75 9^a of the laterally-projecting devices 9 at the upper end of the follower will assume such a position that they can pass between the points of the teeth 12 on the bars 8 and the 80 portions 13 on said bars that lie above the reduced portions on the devices 9. Thereafter, the follower can be moved toward or away from the rear wall 7 of the garment compartment, the reduced portions on the 85 laterally-projecting devices 9 on the follower sliding freely over the teeth 12 on the bars 8 when the follower is moved rearwardly. After the follower has been moved to the desired position, for example, rearwardly 90 far enough so that it will press the garments together when the follower is in a vertical position, the lower end portion of the follower is swung downwardly, thereby causing the spring-actuated bar 10 to engage the 95 retaining devices 11 and ride over the teeth thereon until the follower assumes a position parallel, or approximately parallel, with the rear wall 7 of the garment compartment.

A follower of the construction above described holds the clothes in the garment compartment in a flat condition and prevents them from moving around when the trunk is in transit, owing to the fact that said follower extends nearly the full length of the garment compartment and is secured at both its upper and lower ends; such a follower can be adjusted easily; and still another desirable feature of such a follower is that it 105 cannot jump off the bars on which it is mounted when the trunk is handled roughly or stood on either of its ends, the bars 8 serving as the supporting means for the follower when the trunk stands on one of its ends, as 110 shown in Fig. 1, and the bars 11 serving as the supporting means for the follower when the trunk stands on its other end.

In relatively shallow wardrobe trunks of the so-called "steamer trunk" type it is the 115 usual practice to provide the drawer section with one drawer that is relatively deep or high, but comparatively shallow, so that men's shirts can be packed in same in a flat condition. Heretofore, the shirt drawer of a steamer wardrobe trunk had to be completely removed from the drawer section 120 when said drawer was being packed or unpacked, thus making it inconvenient to remove a shirt from the trunk or pack shirts 125 130

in the trunk. In my improved trunk the drawer section B of the trunk is provided with a shirt drawer 3^a that is combined with the guides 4 on which it normally rests in such a manner that said drawer can be packed or unpacked without removing it completely from the drawer section. As shown in Fig. 1, the portion of the drawer 3^a that constitutes the bottom of the drawer when said drawer is in its normal position on the guides 4, is provided with hook-shaped devices 18 that project into elongated slots 19 in the guides 4. When it is desired to pack or unpack the drawer 3^a said drawer is moved forwardly on the guides 4 and then swung downwardly into a horizontal position, as shown in Fig. 1, the devices 18 on said drawer coöperating with the guides 4 to support the drawer and prevent it from being withdrawn completely from the drawer section. After said drawer has been packed or unpacked, it is swung upwardly into operative position on the guides 4 and then moved rearwardly into its normal position in the drawer section. It will thus be seen that by constructing the shirt drawer in this manner I facilitate the operation of packing or unpacking a wardrobe steamer trunk by overcoming the necessity of completely removing the shirt drawer and placing it on the floor or on a chair while it is being packed or unpacked, as has heretofore been the usual practice.

Having thus described my invention, what I claim, and desire to secure by Letters Patent, is:

1. A wardrobe trunk provided with a garment compartment, a follower in said compartment supported in such a manner that one end of same can be swung inwardly or outwardly with relation to the rear wall of said compartment, said follower consisting of a one-piece frame whose portions are

permanently connected together, and a locking means for securing the free end of said follower consisting of a spring-pressed bar arranged transversely of the follower, some distance inwardly from the end thereof, and toothed devices on the vertical side walls of the garment compartment that coöperate with the end portions of said bar. 45

2. A wardrobe trunk, comprising a garment compartment, a follower in said compartment consisting of a rigid frame, rails that coöperate with a means on one end 55 of said follower to support it, a transversely-disposed bar arranged adjacent the opposite end of the follower in such a manner that it can be moved longitudinally of same, and stationary notched devices that are adapted 60 to be engaged by the end portions of said bar.

3. A follower for wardrobe trunks provided at one end with laterally-projecting devices that coöperate with a supporting means on the trunk, a bar arranged transversely of the follower adjacent the opposite end of same, housings on said follower, guiding devices on said bar that project into said housings, and springs in said housings 70 connected to same and to said bar for exerting pressure on said bar in one direction. 65

4. A follower for wardrobe trunks consisting of a rigid frame provided at its upper end with laterally-projecting devices, 75 rails having teeth or notches that receive said devices, a bar arranged transversely of the follower adjacent the lower end of same and adapted to be moved longitudinally of the follower without altering the length of 80 the follower, coöperating guiding portions on said follower and bar, a resilient means that tends to move said bar in one direction, and notched retaining elements at coöperate with the end portions of said bar. 85

EDWARD J. MAHER.
